UNITED STATES PATENT OFFICE.

ALFRED W. MORGAN, OF INDIANAPOLIS, INDIANA, ASSIGNOR TO LOUISA G. MORGAN, OF SAME PLACE.

WELL-LINING APPARATUS.

SPECIFICATION forming part of Letters Patent No. 257,046, dated April 25, 1882.

Application filed February 28, 1882. (No model.)

To all whom it may concern:

Be it known that I, ALFRED W. MORGAN, a resident of Indianapolis, in the county of Marion and State of Indiana, have invented a new and useful Improvement in Apparatus for Lining Wells, of which the following is a specification, having reference to the accompanying drawings.

My invention relates to an improved mold for forming a continuous cement or concrete lining for wells, my object being to construct a mold that will keep a definite size and shape while the concrete lining is forming, but which may be readily released after the concrete has become hardened.

My invention consists in the means of retaining the outside and inside of the mold in shape, and manner of operating it, as herein-after fully described.

In the accompanying drawings, Figure 1 is a perspective view of my invention. Fig. 2 is a top plan. Fig. 3 is a vertical section through *x x* on Fig. 2.

Like letters refer to like parts in all figures.

A is the cylindrical tube, open at both ends, and having the top end flared, as shown at *a*. It is made of a sheet of metal rolled into tubular form, and having the edges of the sheet overlapping, but not fastened permanently together. Said edges are held together by means of a latch, *D*, which is pivoted to one edge of the sheet and hooks over a projecting stud, *e*, on the other edge, as shown in Fig. 1. The free end of latch *D* is turned outward and engages the guard *E* when the latch is lifted off the projecting stud *e*, thus limiting the expansion of the tube. The edges of sheet *A* are still further held in place by the cleats *F F*, which are riveted to one edge and overlap the other edge, as shown. Within the tube *A* is another tube, *B*, similarly formed of a sheet of metal rolled together, but not flared at the top, and somewhat longer than *A*. Tube *A* is so rolled that the elasticity of the sheet tends to expand it, and tube *B* is rolled so that it tends to contract. The central portion of tube *B* is braced and held firmly in shape by means of a metallic ring, *H*, which engages the peculiarly formed and arranged lugs *h h'*, and having a bail, *H'*, for lifting it by. Said lugs are riveted

to the interior of the tube, and are arranged alternately around the interior circumference, lugs *h* forming hooks tapering outward and lugs *h'* tapering inward, so that as ring *H* is dropped into the tube the sheet is caused to closely conform to the shape of said ring. By using different-sized rings the tube *B* is made of different diameters, as may be required. The top of tube *B* is steadied and held in place centrally within tube *A* by the braces *b*, extending radially outward from *B* and resting against the interior and on the top edge of *A*. An annular space is thus formed between tubes *A* and *B*, the top of which space is open and the bottom closed by a wooden ring, *C*, the outside diameter of which is the same as that of the tube *A*. Three or more short blocks, *c*, are fastened on the top of ring *C*. Said blocks fill snugly between tubes *A* and *B* and serve to keep said tubes and rings *C* in true relative position.

The operation of my invention is as follows: The tube *A* having been drawn together, the latch *D* engaging lug *e*, it is placed on ring *C*, and tube *B* is placed in position centrally within tube *A*. The whole is now suspended over the mouth of the well by chains attached to the top edge of *A*, as shown, and suspended from a frame-work or derrick. Ring *C* is held up against the bottom of *A* by means of the bent rods *r r*, suspended by chains *o* from a derrick in the usual manner, well-known in well-walling apparatus. Cement concrete is now poured into the space between tubes *A* and *B*, filling it nearly up to the flaring-point at *a*. Said concrete is allowed to remain and harden until it is self-sustaining. When it has become hard the latch *D* is raised from lug *e* and the tube *A* expands, the expansion being limited by the guard *E*. The ring *H* is now lifted out of contact with the inclined lugs *h* and *h'*, and tube *B* contracts, thus leaving the concrete-tube free from the mold. The ring *C*, carrying the new-formed section of concrete tubing, is now lowered by the derrick into the well until the top edge of said concrete is near the bottom of the mold. The mold is now readjusted and more concrete poured in, the process being repeated till ring *C* reaches the bottom of the well. Rods *r r* are now withdrawn, the ring *100*

C being left at the bottom of the well. A smooth continuous lining is thus formed without having to descend the well.

I claim as my invention—

- 5 1. The above-described means of forming a continuous concrete well-lining, consisting of a mold of the form and construction described, suspended over the well, and having its lower end closed by an annular plate or ring independently suspended, and adapted to be lowered into the well with the lining while the mold retains its position, as set forth.
- 10

2. In combination with the outward-expanding tube A, the latch D, lug e, and guard E, substantially as and for the purpose set forth. 15

3. In combination with the inward-contracting tube B, ring H and lugs h and h'.

ALFRED W. MORGAN.
